UNITED STATES PATENT OFFICE.

JACOB M. ROTH, OF PITTSBURGH, PENNSYLVANIA.

MOLD.

1,165,025.

Specification of Letters Patent. Patented Dec. 21, 1915.

Application filed March 27, 1915. Serial No. 17,486.

To all whom it may concern:

Be it known that I, JACOB M. ROTH, a citizen of the United States, residing at Pittsburgh, in the county of Allegheny and State of Pennsylvania, have invented certain new and useful Improvements in Molds, of which the following is a specification, reference being had to the accompanying drawings.

10 This invention relates to molds and more particularly to metal molds.

The present invention has for its primary object to provide improved means whereby an interior or exterior metal lining may be quickly and perfectly welded upon a core body, said welded metals being subsequently drawn and fashioned or shaped into various commercial articles.

15 It is another very important object of the invention to provide a mold of the above type which is of such construction that the formation of air or blow holes in the poured metal is precluded and a very compact or homogeneous casting produced.

20 More specifically stated, the present invention is designed with a view to producing a mold structure having means for positioning a core therein and into which the metal may be uninterruptedly poured, said mold being provided with means to admit of the escape of the air and gases displaced by the molten metal.

25 It is an additional object of the invention to provide a metal mold including a body section and a removable head section, said body section being formed at its base to provide a seat for the core body, said head section being recessed to permit of the expansion of the core when heated by the molten metal and having two openings therein into one of which the metal is poured into the body of the mold while the air escapes through the other of said openings, the molten metal rising in the openings 30 in the head section of the mold and creating a hydrostatic pressure upon the molten metal around the core body.

35 With the above and other objects in view, my invention consists in the novel features of construction, combination, and arrangement of parts to be hereinafter more fully described, claimed, and illustrated in the accompanying drawings, in which,

Figure 1 is a vertical section through a

metal mold constructed in accordance with 55 the preferred embodiment of the invention; Fig. 2 is a similar view taken on the line 2—2 of Fig. 1; Fig. 3 is an enlarged top plan view of the removable head section of the mold; Fig. 4 is a bottom plan view thereof; Fig. 5 is a top plan view of the body section of the mold; Fig. 6 is a sectional view similar to Fig. 1, showing a slightly modified construction of the mold for casting an exterior metal lining upon a tubular core 65 body; Fig. 7 is a similar view of another form of the invention to be used for casting an interior lining upon a tubular core; and Fig. 8 is a vertical section illustrating still another type of the mold employed for the 70 simultaneous casting of interior and exterior metallic linings upon a tubular core.

In the accompanying drawings, I have illustrated one practical embodiment of my invention, wherein 5 designates the body section of the mold which may be constructed from cast iron, steel, carborundum, aluminum, or other material. This mold body is of elongated form, as shown, and may be round, square, hexagonal, or of any other 75 desired cross-sectional configuration. The core receiving chamber 6 of the mold is provided at its base with an annular inclined or beveled shoulder 7 communicating with the seat 8 which is adapted to receive the 80 lower end of the steel or iron core, indicated at C. This core seat is of smaller diameter than the diameter of the chamber 6, and the beveled or inclined shoulder 7 serves to direct the lower end of the core 85 into and upon said seat when the same is inserted into the mold so that the core body will be concentrically spaced from the mold wall. Upon the upper end of the body 5 of the mold and at diametrically opposite 90 points, the mold wall is formed with the outwardly projecting lips or lugs indicated at 9, whereby opposed recesses 10 are produced in the upper edge of the mold. The particular purpose of these recesses will be 95 hereinafter referred to. In the top face or upper edge of the body 5 of the mold, a continuous groove or channel 11 is formed, said groove extending in concentric relation to the perimeter of the mold body. 100

In conjunction with the body 5 of the mold, a removable head section, generally indicated by the numeral 12, is employed.

This head section of the mold is preferably constructed of the same metal as the body 5 and includes a body portion 13 of substantially rectangular form in cross-section, 5 upon one end of which an enlargement 14 is formed which is of the same contour in plan as the upper end of the mold body 5 and is formed at its outer edge with a continuous longitudinally projecting flange 15 10 which is adapted to engage exteriorly upon the upper end of the mold body. At the base of this flange 15 and in spaced relation thereto, a continuous rib 16 is formed, said rib being adapted for engagement in the 15 groove or channel 11 in the upper edge of the mold body 5.

17 designates a packing strip which is first arranged in the channel 11. Thus, when the heavy head section 12 of the mold is arranged in position, the rib 16 engaging upon said packing strip forces the same tightly into the groove or channel, thus producing a fluid-tight connection between the opposed end faces of the two sections of the mold. 25 The rectangular body 13 of the removable mold head is formed with spaced longitudinally extending openings 18 therein, preferably, though not necessarily, of the cross-sectional form shown in Fig. 3. These openings taper longitudinally and gradually decrease in cross-sectional area from the upper end face of the mold head to the bottom face thereof. The integral web 19 separates these 30 openings from each other and, owing to the tapering form of said openings, the web 19 consequently gradually increases in thickness from its upper to its lower end. This lower end of the web 19 terminates at a point slightly above the seating face of the head 12 35 which rests upon the upper end of the mold body 5 whereby a recess, indicated at 20, is formed for the reception of the upper end of the core C. The lower end face of the web 19 is tapered or inclined upwardly from 40 its center, as shown at 21, to the lower ends of the respective openings 18. At the opposite ends of the recess 20, the walls of the mold head between the lower ends of the openings 18, are outwardly beveled or inclined, as at 22, to the bottom seating face of 45 said head. It will be observed, from reference to Fig. 1 of the drawings, that when the head is in place upon the upper end of the mold body, the top face of the core member 50 C, within the recess 20, is spaced from the lower end face of the web 19. The lower ends of the openings 18 through the mold head are disposed in registering relation 55 with the recesses 10 at the upper end of the mold body 5.

Assuming that the core member C has been arranged within the body of the mold and the head section 12 properly placed in position upon the upper end of said mold body, 60 as shown in Fig. 1, the molten metal is

poured into one of the openings 18 in the head section of the mold and gradually collects within the mold chamber 6 around the core. It is to be understood that any suitable flux 70 may be employed for creating a weld or union of the two metals. As the metal collects or rises in the body of the mold, the air and gases are expelled therefrom through the other of the openings 18. The provision of the beveled or inclined faces 22 at the opposite sides of the upper end of the core C, facilitates the expulsion of such air and gas. Thus, there may be an uninterrupted flow of 75 the molten metal into the mold, and all possibility of the formation of air or blow holes in the metal precluded, owing to the means which I have provided for the ready escape 80 of the air which is displaced by the inflowing metal. The pouring of the metal continues until the same substantially fills the two openings 18 in the head section of the mold. The filling of these relatively large 85 openings creates a hydrostatic pressure upon the molten metal in the body 5 of the mold so as to closely compact or unite the molecules of the metal and thus form a homogeneous lining or coating around the core C. 90

The metal core which has been provided with the exterior lining or coating of copper or other metal, in the manner above described, is removed by simply removing the head section of the mold from the body 5, it being understood, of course, that the metal within the openings 18 in said head section is thus cut or broken off from the lining around 100 the core. The rod or billet of metal is now removed from the mold and may be rolled and drawn for manufacture into various commercial articles.

My improved mold is primarily designed 105 for the purpose of casting and welding copper upon a steel body or core. These two metals, after being welded together, may be fashioned into wire to be employed for various purposes, lightning rods, hoops, and 110 numerous other articles for which such a composite metal might be found particularly desirable. It is, of course, apparent that the present invention is, in nowise, restricted to use in conjunction with a core of cylindrical 115 form, but the mold may be employed in the provision of such lining sheets upon a core member of polygonal form in cross-section, it being understood, of course, that the mold chamber will be of corresponding shape. 120

Referring now more particularly to Figs. 6, 7 and 8 of the drawings, it will be observed that I have shown therein, several mold constructions, each embodying the fundamental principle of the device as above set forth, whereby a tubular core may be provided with either an exterior or interior metallic lining, or may be simultaneously provided with both interior and exterior linings. Considering first, the mold as illustrated in 130

Fig. 6, the body 5 thereof is of substantially the same construction as that above referred to; but the head section 12 is of slightly different form. In this type of the mold, the 5 head section is provided with spaced tubular extensions 24 which are integrally connected to the body of said head section which is adapted to be arranged upon the upper end of the mold body, as previously explained. 10 The bores or openings through the spaced portions 24 of the removable head are similar in shape to the openings 18 shown in Fig. 1, and communicate at their lower smaller ends with the metal receiving chamber of the 15 mold body 5. 25 designates the steel tubular body in each end of which a plug 26, preferably of fire clay, is inserted. This tubular body, at its lower end, is seated upon the base wall of the mold chamber and the 20 upper end thereof extends into the circular recess 27 in the head section of the mold, said recess being formed in the face of the connecting wall between the tubular extensions 24 of said head. The molten metal is then 25 poured into one of the extensions 24 and collects around the tubular body 25 as it gradually rises in the mold chamber.

In Fig. 7, I have illustrated the manner of providing an interior metal lining upon 30 a tubular steel body. This tubular body 28 of the composite metal rod or billet to be produced, itself constitutes the body section of the mold. The lower end of this tubular steel body is seated in an annular groove or 35 channel 30 formed in the upper face of a base 29. This base is also provided with a central seat or socket 31 to receive the lower end of a core rod 32. The head section 33 of the mold is of somewhat smaller size than 40 those above referred to, and upon one end is provided with the annular flange 34 for engagement upon the exterior of the tubular body 28 at its upper end. An annular packing strip or ring 35 is arranged between the 45 contacting end faces of the tubular body 28 and the head section 33 of the mold. A similar annular packing strip 36 is also disposed between the outer wall of the annular recess 30 in the base 29 and the outer peripheral face of the tubular body 28. The 50 construction of the head member 33, in other respects, corresponds with the invention as disclosed in Fig. 1 of the drawings, said head being provided with spaced longitudinally extending openings 37 and the recess 38 to receive the upper end of the core rod 32 and permit of the expansion of the 55 same.

In Fig. 8 of the drawings, I have shown 60 still another mold construction whereby the tubular steel center or body of the composite metal rod to be produced by means of the present invention, is arranged within the mold body and engaged at its lower end 65 upon the annular seat 39 formed upon the

base thereof. This bottom face of the mold chamber is also centrally formed with a circular socket or seat 40 to receive the lower end of a core rod 41 and concentrically positioned the same with respect to the tubular 70 body, indicated at 42. The head section 43 of the mold has the spaced tapering openings 44 formed therein and the lower narrower end of each of these openings is divided by a web 45. The lower face of the 75 mold head between the openings 44 has the recess 46 formed therein to receive the upper end of the core 41 and the end face of this core is spaced from the base of said recess for the purpose hereinbefore referred to, 80 while the upper end of the tubular metal body 42 is spaced in a similar manner from the web 45. It will be understood that, in the use of this type of the mold, the molten metal is poured into one of the openings 44 85 and flows downwardly and upon opposite sides of the web 45 and into the space between the wall of the mold body and the outer face of the tubular body 42 and also into the space between the inner face of this 90 body and the periphery of the core rod 41. Thus, it will be seen that the tubular steel body of the composite metal rod will be simultaneously provided with the interior and exterior linings of copper or other metal. 95

From the foregoing description, taken in connection with the accompanying drawings, it will be seen that I have produced a simple, reliable and effective metal mold for quickly and perfectly applying a lining 100 sheet of copper or other metal to a body of steel or other relatively hard metal. The formation of air holes in the molten metal is effectually obviated by the provision of the means above referred to, whereby the 105 ready escape of air and gas is permitted from the body of the mold. By means of my invention, it will, therefore, be manifest that the molten metal may be continuously poured into the mold until the same 110 has become entirely filled. It will also be seen that provision is made for the expansion of the steel core under the heat of the molten metal so that the head section of the mold will not be raised or elevated from the 115 upper face of the mold body. A substantially fluid-tight joint is also formed between the two sections of the mold so that the escape of the molten metal is obviated. The device, as a whole, is of exceedingly 120 simple construction, and provides means whereby the provision of metal lining sheets upon steel centered rods may be greatly facilitated.

I have illustrated, in the drawings, certain forms of the several types of molds referred to; but it is to be understood that the present invention contemplates the construction of said molds in various other shapes and sizes. I have also reserved the privi- 125 130

lege of resorting to various modifications in the form, proportion, and arrangement of the several structural features of my invention which may be fairly embodied within the spirit and scope of the appended claims.

Having thus fully described my invention, what I desire to claim and secure by Letters Patent is:—

1. A metal mold of the character described having a pouring opening and an air escape opening in its upper end provided with a recess in the division wall between the lower ends of said openings, and a metal core adapted to be entirely disposed within the mold and having its upper end disposed in said recess.

2. A mold of the character described including a body, a removable head section adapted to be arranged upon said body and having a pouring opening and an air escape opening, said head being also provided with a recess between said openings to receive the upper end of a rod concentrically arranged in the mold body to permit of the expansion of the rod when the same is heated by the metal poured into the mold.

3. A mold of the character described including a body, a removable head section having a pouring opening and an air escape opening therein, said head being further provided with a recess between the lower ends of said openings to receive the upper end of a metal rod concentrically arranged in the mold body and permit of the expansion thereof when heated by the metal poured into the mold, and means for establishing a fluid-tight joint between the contacting faces of the mold body and the removable head section.

4. A mold of the character described including a mold body provided with means at its base for concentrically positioning a metal rod therein, a removable head adapted to be arranged upon the upper end of said body and having spaced openings therein, said mold body being provided with recesses at its upper end leading from the respective openings in the head section and communicating with the metal receiving mold chamber, the molten metal being poured through one of the openings in said head into said chamber, and the air and gas being expelled from said chamber through the other opening in the head.

5. A mold of the character described including a mold body provided with means in its base to receive and concentrically position a metal rod therein, a removable head adapted to be arranged upon the upper end of said body and provided with a recess to receive the upper end of said rod and permit of its expansion, said head being further provided with longitudinal openings at opposite sides of said recess through one of which the molten metal is adapted to be

poured into the mold, the air and gas being expelled from the mold through the other of said openings.

6. A mold of the character described including a mold body provided with means in its base to receive and concentrically position a metal rod therein, said body being provided in its top face with a groove to receive a packing strip, a removable head section having a seating face and a rib formed thereon to engage said packing strip and compress the same within the groove of the mold body, said head having spaced openings therein through one of which the molten metal is poured into the mold body and the air and gas being expelled from the mold through the other of said openings.

7. A mold of the character described including a mold body provided with means on its base to receive and concentrically support a rod therein, a removable head section adapted to be arranged upon the upper end of the mold body and having spaced longitudinally tapering openings formed therein separated by a medial web the bottom face of which is recessed to receive the upper end of the rod and permit of its expansion when heated by the molten metal poured into the mold through one of said openings, the other opening in the head permitting of the escape of air and gas in the mold.

8. A mold of the character described including a mold body provided with means in its base to receive and concentrically support a rod in position therein, a core rod seated in said mold, a removable head section adapted to be arranged upon the upper end of the mold body and provided with spaced longitudinally tapering openings to communicate with the chamber of the mold at diametrically opposite points, said openings being separated by a medial web having its lower end recessed and its end face beveled in opposite directions toward the respective openings, the opposed walls of said recess at its outer end being outwardly inclined, said recess receiving the upper end of the rod to permit of its expansion when heated by the metal poured into the mold through one of said openings, the air and gas being expelled from the mold chamber by the inflowing metal through the other of said openings.

9. In a metal mold for providing a metallic lining upon a metal body, a mold body, a metal core body in said mold, a pouring head provided with spaced openings and a recess in one end between said openings to accommodate the metal body and permit of its expansion, the molten metal being poured into the mold around said body through one of said openings and the air and gas expelled from the mold by the entering metal through the other of said openings.

10. In a metal mold for forming a metal-

lic lining upon a metal body, a mold body, a metal core body seated in said mold, a pouring head adapted to be seated upon the upper end of the mold body, said head being provided with spaced longitudinally tapering openings and having a recess formed therein between the smaller ends of said openings and connecting the same, the base of said recess being inclined inwardly from the center of the head to the respective openings, said recess receiving the end of the metal body in the mold and permitting of

its expansion when heated by the molten metal, the metal being poured into the mold body through one of said openings and the 15 air and gas expelled by the inflowing metal through the other of said openings.

In testimony whereof I hereunto affix my signature in the presence of two witnesses.

JACOB M. ROTH.
